UNITED STATES PATENT OFFICE.

FRANK M. MACKEY, OF LA PORTE, INDIANA, ASSIGNOR TO HIMSELF, AND EDWARD MORF AND GUSTAV B. MORF, BOTH OF CHICAGO, ILLINOIS.

MILLING APPARATUS.

SPECIFICATION forming part of Letters Patent No. 293,047, dated February 5, 1884.

Application filed April 9, 1883. (No model.)

To all whom it may concern:

Be it known that I, FRANK M. MACKEY, a citizen of the United States, residing in La Porte, in the county of La Porte and State of Indiana, have invented a new and useful Improvement in Milling Apparatus, of which the following is a specification.

To produce the best quality of flour it is desirable, as far as possible, to clean or separate the dirt, down, fluffy stuff, and other impurities from the wheat before the berry is broken to any considerable extent, or any flour produced to mix with the impurities. It is also desirable to loosen and separate the middlings or flour portion from the bran in as large and uniform-sized particles as possible, and also without breaking or pulverizing the bran any more than can be helped, because the coarse grade of middlings can be much more perfectly and easily purified, and if the bran is not broken up and pulverized the middlings or flour can be more completely separated therefrom without danger of having fine particles of bran mixed with the flour.

The object of this invention is to provide a means whereby these results can be attained more perfectly than heretofore, and by cheaper and more simple machinery, and at an expenditure of less power.

Heretofore the wheat has usually been passed between two opposing surfaces or stones provided with a dress designed to produce more or less of a grinding, tearing, or triturating action, or else it has been passed between two simple rolls running together. In the first case, flour is produced in considerable quantities before the dirt and impurities are loosened and can be separated, owing to the grinding or rasping action of the opposing surfaces, and in the latter case the berry or kernel of wheat is simply crushed or flattened and glazed between two surfaces, which press it only on two sides, and the tendency is rather to embed the dirt in the middlings than to loosen and separate it from the wheat; and rolls have little or no tendency to rub off or remove the fine down upon the outside of the wheat at its germ end; and neither with the rolls nor with opposing surfaces having a grinding action can anything like uniformity in the size of the particles be produced. Sometimes, also, mill-

ing apparatus having a smooth-surfaced or metallic dress has been employed. Such apparatus has ordinarily consisted of flat or horizontal disks having peripheral corrugations, as shown in the Patent No. 223,056, to Jonathan Mills, or else of a frustum-roll and case having nearly vertical operating surfaces, as shown in the Patent No. 260,750, to Gratiot. In the former, in order that the centrifugal force may feed or carry the kernels of wheat out between the horizontal disks or the corrugations therein, it is necessary to revolve the disks at a very high speed, unless the dress or corrugations be made too short to do effective work, and in the latter the same necessity exists to prevent the kernels passing by their gravity through the apparatus before it does its work, unless the frustum be made of an impracticable length or height. The high speed not only heats the apparatus, thus greatly diminishing its durability, but also heats the wheat or middlings, thus occasioning great difficulty in the subsequent bolting and purifying operations, as heated material causes the meshes in the bolting-cloth to clog, and the heat also injures the flour produced. The great speed at which such apparatuses must be run, and the fact that the grinding or operating surfaces thereof must also be set closely together in order to do any effective work, causes great irregularity in their operation upon the grain, and prevents anything like uniformity in the middlings produced.

In the present invention I subject the wheat to a rubbing and rolling action between two conical disks having a smooth beveled dress or furrows, so as to produce no tearing or grinding action on the wheat. The effect of rubbing and rolling the wheat between these two smooth beveled dressed conical disks is to thoroughly loosen, separate, and rub off the dirt, dust, down, and other impurities from the wheat and thoroughly clean and polish it. The wheat, after being rubbed and rolled in this manner until the dirt and impurities are thoroughly loosened, is then screened, whereby the impurities, together with such small portions of middlings or flour as may be produced by breaking or splitting some of the berries, are separated from the wheat and conducted to a middlings-purifying apparatus. I

then pass the wheat between a similar set of conical disks, set a little closer together, whereby the berries of wheat being subjected to a similar rubbing and rolling action are with 5 very great uniformity split or divided into two parts along the seam of each berry, whereby all dirt or impurities in the seam of the wheat and elsewhere are loosened and rubbed off, and, passing thence over another sieve, are 10 separated from the wheat together with such small portions of the middlings as may also be loosened, and conducted to the purifiers. By these two preliminary steps or operations all the impurities may be, by this means, very 15 completely separated and removed from the wheat without producing and mixing with the impurities any great or material proportion of the middlings or abrading from the wheat any of the bran; and the wheat-berries will 20 be found to be simply divided in half along the seam of the wheat, leaving particles of very uniform size and shape. By subjecting the thus cleaned and divided wheat to the action of similar conical disks set still closer together, the middlings by this same rubbing and rolling action will be loosened from the bran without materially cutting or abrading the bran, and each successive step or operation will tend to leave the particles of uniform 25 size, which of course very much facilitates the purification of the middlings. The two conical disks, of which the lower one is the runner and cone-shaped, while the upper one is stationary and dish or cone-shell shaped, have 30 their conical or operating surfaces inclined at a comparatively small angle to the base of the cone, so that the combined action of gravity and the centrifugal force will cause the grain to be carried properly through between the disks 35 in such time as to cause them to efficiently do their work while running at such low rate of speed and degree of pressure upon each other (or the grain between) as to occasion no difficulty from heating the apparatus itself 40 or the material being operated upon. I find by experience that better results may be produced both as regards uniformity in the size of the middlings and in respect to the capacity of the apparatus and the power required 45 to run it, by employing disks whose operating-surfaces have a pitch of about one in height to nine in diameter of the cone, and I would recommend the employment of such in practicing my invention. By so doing it will be 50 found that the disks run very light and free, and the grain will simply be rolled over and over between them, loosening the dirt and down, and splitting or dividing the kernels in half as the highest portions of the dress on 55 the two disks oppose or pass each other. The dress of the lower or revolving disk consists of curved furrows extending spirally from center to periphery, the furrows being deepest near the center and gradually shallowing to 60 the periphery. The lands between the furrows widen from center to periphery and incline smoothly and gradually from their high-

est portion or ledge to the deepest portion of the adjoining furrow on one side of the land and the ledge being curved or rounded off into 70 the adjoining furrow on the other side. The furrow being deepest at the center or eye, the grain can readily pass down along the furrow from the center or slow-running part of the disk before it is much operated upon or encounters much resistance. The upper disk is provided with a similar dress, except that the furrows are straight instead of curved, so each of the lands or furrows of the upper disk will 75 lie across or oppose two of the curved lands or furrows of the lower disks or portions thereof, which prevents the lands and furrows of the two disks coinciding or fitting snugly together, and thereby causes the disks to operate with greater uniformity upon the grain, 80 and to give it a rolling motion between them.

In the accompanying drawings, which form a part of this specification, and in which similar letters of reference indicate like parts, Figure 1 is a vertical central section of a device embodying my invention. Fig. 2 is an enlarged sectional view of the trampot and sleeve. Fig. 3 is a plan view of the bridge-tree upon which the spindle or shaft is supported. Fig. 4 is a top view of the coping or outside covering. Fig. 5 is a bottom view of the same. Fig. 6 is a top view of the upper conical disk or reducer. Fig. 7 is a bottom view of the same. Fig. 8 is a top view of the lower conical disk or reducer. Fig. 9 is a top 90 view of the sieve. Fig. 10 is a side view of the upper and lower reducers in position.

In the drawings, A represents a cylindrical or conical chamber inclosing the apparatus and constituting the frame upon which the 105 parts are mounted, or to which they are secured.

B is the bridge-tree upon which the shaft or spindle C is supported. It is secured to brackets or flanges a upon the interior of the chamber A by suitable bolts.

D and D' are respectively the upper and lower conical disks or reducers. The lower disk, D', is secured fixedly to the spindle C, so as to revolve with it. The upper conical disk, D, is held stationary, and is supported from the coping or outer covering, E, to which it is secured by set-screws d and hand-screws d', which serve also to adjust the upper disk, D, in proper position to the lower disk, D'. The coping E is provided with an interior 110 shoulder, e, adapted to fit the exterior shoulder, e', on the disk D, for the purpose of guiding and truing the same. The coping E is secured to a ring, b, which itself is supported upon the flanges b', secured to the chamber or frame A. The ring b is provided with a projection, b², on its upper surface, which fits in a corresponding groove in the base of the coping E, whereby the coping is properly centered or trued in position. The hopper F is provided with screw-threads, whereby it is secured to the upper or stationary reducer, D, at its central opening, and thus supported.

G represents a dished sieve, arranged under

the reducers D and D', upon which the material is thrown by the centrifugal action of the revolving disks. This sieve is supported by a collar, g, which fits around a cam-sleeve or 5 collar, g², secured to the shaft C by a set-screw, g³. The collar g, which forms part of the sieve, or to which the sieve is secured, is made of skeleton form or provided with openings g⁴, through which the coarser material may fall 10 into the hopper of the next reducer below. The cam or eccentric sleeve g² is provided with a horizontal flange, upon which the sieve-collar g rests, so that the sieve cam-sleeve supports the sieve.

15 H is a spring attached to the frame of the sieve near its middle, and at each extremity to the frame of the machine. This spring prevents the sieve from revolving with the shaft C, but permits it to yield or move slightly in 20 either direction, so that the eccentric or cam sleeve g² is made to give the sieve a rapid vibratory circular motion or oscillation.

H' is the dished bottom of the sieve, which collects the finer particles of dirt and middlings loosened from the wheat by the action 25 of the disks D D', and which fall through the sieve.

H² is a spout or conduit attached at one side to the bottom H', for conducting away this 30 finer material to the purifier. This spout is secured rigidly to the bottom, and has the same vibratory motion as the sieve itself.

K is a collar secured to the shaft C by a set-screw, k, and upon which the shaft and all 35 mounted thereon are supported. The collar K is supported with a shoulder or flange, k', which rests upon a sleeve, k², having a groove, k³, on its upper surface. The groove k³ is made wider than the flange k', so as to form a 40 recess for the lubricant. The sleeve k² rests upon the adjusting-lever L, which is fulcrumed to the bracket l, attached to the bridge-tree. The lever L is provided with an eye or hole 45 encircling the shaft C, and its height is adjusted by means of the rod l' and threaded hand-wheel l², supported on the bracket l' on the exterior of the frame A.

k⁴ is a ring encircling the sleeve k², and k⁵ are set-screws passing through brackets or 50 ears k⁶ on the bridge-tree, by which the shaft C may be adjusted and properly centered in position laterally.

M M are arched braces or frame-pieces secured to the frame A, and in which the shaft 55 C has its upper bearing.

The upper or stationary disk or reducer, D, has its operating-surface made of an interior conical or dish shape. At the eye a cavity, m, for the reception of the grain, immediately 60 surrounding the eye, is left hollowed out. From the edge of this grain-cavity radial lines or grooves m' extend to the periphery, as shown clearly in Fig. 7. The material of the disk between these grooves is cut with a beveled surface, as indicated at Fig. 10, where the edge of the plate is shown. The lower disk 65 or runner is made of an exterior conical form

to counter the stationary disk, and is dressed in the same way, except that the grooves or lines are made curvilinear from the eye to the 7c periphery, as indicated in Fig. 8, and that the grooves m² are made of gradually-increasing

depth from the periphery to the center, in order to effect the feeding of the grain. The 75 dress is smooth-surfaced so as not to abrade or tear the grain. The runner-disk D' revolves in the direction indicated by the arrow in Fig.

10, so that the grain or material between the plates is subjected as the disk revolves to gradually increasing or wedging pressure from 80 the lowest portion of the grooves to the highest portion of the dress. The action of the

disks is to give a rolling motion to the grain or material between them, so that the disk D' revolves very freely and with little friction, 85

and requires a comparatively small amount of power to drive it in proportion to the capacity of the machine. The upper disk, D, is somewhat larger than the lower one, so as to discharge the material downward from its 90 periphery to the sieve below. By reason of the

conical form of the reducers D D', and the fact that the lower one is the runner or rotary one, the centrifugal action tends to lift or 95

throw the material against the surface of the upper disk, and thereby materially increases 100 the capacity of the reducers to retain the grain between the plates—that is to say, the upper disk or interior cone surface opposes itself to the centrifugal tendency of the seed

to seek the periphery in the rapid rotary movement given to the grain by the lower disk. Two or more sets of reducers D D' 105

and intermediate screens or sieves, G, may be arranged on a single shaft; but I think for the 110 operation of cleaning and removing the impurities from the wheat two sets are preferable, the lower set being simply adjusted or set close enough together to split or divide the berries in half.

115 The purifier consists of a cylinder or chamber, O, provided with one or more revolving disks, o, secured to a shaft, o'. The shaft o' is journaled in appropriate bearings, and is driven by a pulley, P. The material falls

from the spout or conduit upon the rotating disk o near its center. The revolving disk o has a fluted surface, and operates to distribute 120 the material in a thin sheet or spray from its periphery, so that it will be more sensitive to

the action of the blast. Q is an arched pipe leading from the top of the cylinder to a fan or suitable device for producing a suction 125 through the cylinder. The air is admitted

through ports q near the bottom of the cylinder. A stationary deflecting-plate or conical disk, o², is arranged above the rotating disk o, to deflect the blast toward the periphery of 130 the chamber O. R is a funnel arranged below the revolving fluted disk o, for the purpose of conducting and delivering the material upon the revolving fluted disk o below; and Q' is a dome below said funnel, for directing the blast or suction up through the funnel.

The funnel R is preferably given a fluted or interior stepped surface. Two or more revolving disks o may be arranged in a series.

T is the discharge-openings, through which 5 the purified middlings are delivered.

The reducers D and D', or their operating-surfaces, should be made of iron or similar material.

The apparatus herein shown or described 10 for purifying the middlings as they come from the reducers and screens I believe possesses certain novel and patentable features of invention, and, not being herein claimed, I expressly reserve the same for a future application for a patent.

I claim—

1. The combination, with a series of lower revolving conical disks or reducers provided with smooth-surfaced spiral dress and secured 20 to a vertical shaft, of a series of upper stationary opposing conical disks or reducers having a smooth-surfaced radial dress, and a series of dished sieves having a circular vibrating motion, substantially as specified.

2. The combination of chamber or frame A, bridge-tree B, shaft C, lower revolving conical reducers, D', secured thereto, and provided with smooth-surfaced spiral dress, stationary upper opposing conical reducers, D, provided 30 with smooth-surfaced radial dress, hoppers F, copings E, dished screens G, and eccentrics g², for giving to said screens a circular vibrating motion, substantially as specified.

3. The combination, with the bridge-tree 35 B, of the shaft C, collar K, secured to said shaft, and provided with flange k', and sleeve k², provided with an annular groove or recess, k³, in its upper end, to receive the downwardly-projecting flange k' of the collar K, and thus 40 form also an oil-receptacle, substantially as specified.

4. The combination of sieve G, spring H, secured to said sieve and to the stationary frame, and a shaft and eccentric for communicating to the sieve a circular vibratory motion, substantially as specified.

5. The combination of under revolving conical reducer, D', stationary opposing conical reducer D, coping E, set-screws d and hand-screws d', hopper F, provided with screw-threads, whereby it is secured to reducer D, and chamber A, substantially as specified.

6. The combination, with the chamber A, provided with interior flanges, b', of ring b, provided with projection b² on its upper surface, coping E, provided with grooved foot secured to said ring, upper stationary adjustable conical reducer, D, hopper F, secured to said re-

ducer, and under revolving conical reducer, D', and shaft C, to which said reducer D' is secured, substantially as specified.

7. The combination of chamber A, coping E, secured to said chamber, upper stationary adjustable conical reducer, D, supported from said coping, and provided with smooth-surfaced radial dress, shaft C, and revolving conical reducer D', secured to said shaft, and provided with smooth spiral dress extending from center to periphery, substantially as specified.

8. The combination of chamber A, coping E, upper stationary conical reducer, D, supported from said coping, shaft C, under revolving conical reducer, D', secured to said shaft, and circularly-vibratory sieve G, supported and operated by eccentric on shaft C, substantially as specified.

9. The combination of dished sieve G, provided with open collar g, shaft C, provided with cam-sleeve g², by which said sieve is supported and operated, spring H, and dished bottom H', provided with discharge-spout, substantially as specified.

10. The combination of chamber A, bridge-tree B, shaft C, collar K, rigidly secured to said shaft, and provided with flange or shoulder k', sleeve k², loosely mounted on said shaft, and provided with grooves k³, adapted to receive shoulder k⁴ and leave an oil-receptacle, 80 90 adjusting-ring k⁵, brackets k⁶, and adjusting-screws k⁷, substantially as specified.

11. The combination, with the shaft C, of the cam-sleeve g², secured to said shaft, and provided with a horizontally-projecting flange 95 or shoulder, of the dished sieve G, and collar g, rigidly secured to the sieve, and provided with an interior shoulder or flange fitting over the flange on the cam-sleeve g², whereby the sieve is supported and operated by the cam-sleeve, 100 substantially as specified.

12. The combination, with the shaft C, of the cam-sleeve g², secured to said shaft, and provided with a horizontal projecting flange or shoulder, of the dished sieve G, collar g, 105 rigidly secured to the sieve, and provided with an interior shoulder or flange fitting over the flange on the cam-sleeve g², and dished bottom H', provided with discharge-spout H², secured to the frame of the sieve, so as to vibrate therewith, substantially as specified.
